CLAIM

I claim the ornamental design for a cosmetic storage case, as shown and described.

DESCRIPTION

FIG. 1 is a top perspective view of a cosmetic tool storage case, showing my new design;

FIG. 2 is a bottom perspective view thereof;

FIG. 3 is a top view thereof shown in a folded state;

FIG. 4 is a bottom view thereof shown in a folded state;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a partial enlarged view taken in FIG. 1.

The dash-dot-dash broken lines illustrate the boundary of the enlarged view and form no part of the claimed design.
